UNITED STATES PATENT OFFICE.

JAMES R. JONES, OF JOHNSTOWN, PENNSYLVANIA.

MOLDER'S FLASK.

SPECIFICATION forming part of Letters Patent No. 656,022, dated August 14, 1900.

Application filed December 28, 1899. Serial No. 741,809. (No model.)

To all whom it may concern:

Be it known that I, JAMES R. JONES, of Johnstown, in the county of Cambria and State of Pennsylvania, have invented a new 5 and useful Improvement in Molders' Flasks, of which the following is a full, clear, and exact description, reference being had to the accompanying drawings, which form a part of this specification.

10 This invention has relation to certain new and useful improvements in molders' flasks, and is designed to provide means whereby a single flask or flask-section may be used for casting two or more objects side by side and 15 for supporting the sand in the flask in such a manner that the latter can be moved from place to place without injuring the molds therein.

With these objects in view the invention 20 consists in a division-piece secured longitudinally within the flask-section and having means for supporting the sand upon each side of it; also, in means carried by said division-piece and by the lateral walls of the flask- 25 section for carrying gagers, which form an additional support for the sand.

The invention also consists in the novel construction and combination of parts, all as 30 hereinafter described, and pointed out in the appended claims, reference being had to the accompanying drawings, in which—

Figure 1 is a plan view of a flask-section provided with my invention. Figs. 2, 3, and 4 are sections taken, respectively, on the lines 35 2 2, 3 3, and 4 4 of Fig. 1; and Fig. 5 is a perspective view of the flask-section, showing the arrangement of the molds therein.

The letter A designates an ordinary flask 40 cope or cope-section, the invention being applicable to both two and three part flasks.

B designates a division-piece which extends longitudinally through the center of the cope, being secured to the end walls thereof by means of flanges b and bolts b', seated in 45 said flanges and the said walls. Said piece consists of an endwise-disposed plate or bar having laterally-projecting flanges b² at its base, provided each with upwardly-projecting pins b³ and with stiffening-ribs b⁴. Se- 50 cured to the inner face of each side wall of the cope is a longitudinal edgewise-disposed

plate C, whose upper portion consists of a series of fingers or projections c. For convenience these plates may, as shown, be made in short sections; but this is immaterial to my 55 invention.

The piece B divides the cope into two mold-chambers, and a mold may be formed upon each side thereof, as shown in Fig. 5, sand-supporting gagers H being hung upon the 60 upwardly-projecting pins b³ and upon the fingers c in the manner shown in Fig. 4. In narrow flasks or where the body of sand to be supported is not large the side plates C might be omitted, the flanges b³ on the division-piece, with or without gagers hung thereto, being depended upon to carry the sand.

The letter S in Fig. 5 designates mold-cavities upon opposite sides of the central division-piece B and formed in the sand S'. 70

By means of my invention, which dispenses with the use of the cross-bars usually employed to hang the gagers from, I am able to provide a flask in which two molds may be made with but little more work than has heretofore been required to make a single mold. In fact, taking into account the time required in the usual practice to properly fit and secure the gagger-bars around the pattern the actual cost in time and labor of making the two 80 molds does not exceed that of making a single mold. The invention also reduces very largely the number of flasks required, as well as the amount of floor and storage space.

The invention is especially valuable in 85 casting narrow elongated pieces, such as switch-pieces and switch-mates, but is also useful in casting many other articles.

I do not wish to limit myself to the particular construction and arrangement which I 90 have shown and described, as changes may be made in the details thereof without departing from the spirit and scope of my invention as set forth in the following claims.

Having thus described my invention, what 95 I claim, and desire to secure by Letters Patent, is—

1. A molder's flask-section, having a longitudinally-extending division-piece therein provided with flanges at its base, and supports for gagers carried by the said flanges.
2. A molder's flask-section having a longi-

tudinally-extending division-piece therein; and upwardly-extending supports for carrying gagger rising from the base of said piece at the sides thereof.

5 3. A molder's flask-section having a longitudinally-extending division-piece therein, formed with lateral flanges at its base, and upwardly-extending pins or projections on said flanges adapted to carry gagger, substantially as described.

10 4. A molder's flask-section having a longitudinally-extending division-piece therein provided with upwardly-extending pins or projections at its sides, and a series of projections secured to the inner walls of the sides of said section, substantially as described.

15 5. A molder's flask-section, having a longitudinally-extending division-piece therein provided with lateral base-flanges, and with laterally-arranged pins or projections rising from said base-flanges, said section also hav-

ing a series of projections secured to each of its side walls, substantially as described.

20 6. A molder's flask, having secured to its side walls a gagger plate or carrier formed with a series of upward projections or fingers substantially as described.

25 7. A molder's flask having a longitudinally-extending division-plate formed with lateral sand-supporting flanges, a series of gagger-supports carried by each of said flanges, and plates secured to the inner longitudinal walls of the flask, and having each a series of gagger-supports at their upper edges, substantially as described.

30 35 In testimony whereof I have affixed my signature in presence of two witnesses.

JAMES R. JONES.
